UNITED STATES PATENT OFFICE

WAYNE H. WORTHINGTON, OF BATTLE CREEK, MICHIGAN, ASSIGNOR TO ADVANCE-RUMELY COMPANY, OF LA PORTE, INDIANA, A CORPORATION OF INDIANA

THRASHING MACHINE

Application filed January 21, 1926. Serial No. 82,874.

My invention relates to a method and apparatus for balancing the reciprocating or vibrating parts of a thrashing machine or grain separator.

5 In the ordinary grain separator there are generally at least two separate reciprocating racks or tables. One is that usually termed the "grain pan" or "grain conveyor", the other as the straw rack. These two racks 10 are driven from a main crank shaft by pitmen or connecting rods which to accommodate other structural parts are placed in planes inclined one to the other. Owing to the fact that the racks are supported by 15 swinging links the included angle between the two planes of these pitmen varies but there is always an average angle between them which may be accurately determined. Experience shows that when driven from a 20 two-way crank shaft with the two crank throws in the same plane, the two vibrating members or racks will most of the time be in balance, they will be out of balance twice each revolution during a travel of the crank 25 shaft subtended by an angle substantially equal to the average angle between the two planes of the pitmen and it is this lack of balance of the heavy reciprocating during a part of the crank shaft travel which sets up 30 the characteristic vibration in a thrashing machine. I have discovered that if instead of being in the same plane the two throws of the crank shaft are in two planes inclined to each other at an angle equal to the average 35 inclination of the planes of the pitmen, the two racks will always be in balance.

The reason for this is that when the two throws are in the same plane, one of the racks will still be going forward after the other 40 rack has changed its rearward direction and started forward. When the crank throws are offset they can be so set that each rack will reverse its direction of movement at the same time. Other objects will appear from 45 time to time throughout the specification and claims.

My invention is illustrated more or less diagrammatically in the accompanying drawings, wherein:

50 Figure 1 is a fragmentary side elevation

showing a thrasher with my driving mechanism in place;

Figure 2 is a plan view showing the crank shaft;

Figure 3 is a vertical cross section on an 55 enlarged scale, taken on line 3-3 of Figure 2;

Figure 4 is a diagram illustrating the conditions of balance in a two throw crank shaft in which the crank pins are 180° apart and 60 not in balance;

Figure 5 is a similar view showing the crank pins arranged so as to balance;

Figure 6 is a diagram showing a three throw crank shaft in which the parts are in 65 balance.

Like parts are illustrated by like characters throughout.

Where I have referred to a two throw and three throw crank shaft I mean a shaft in 70 the first case adapted to operate two pitmen or similar devices, and in the second case adapted to operate three. Such pitmen might be in pairs or singly, or the two throw shaft might as shown have four crank pins 75 operating in two pairs. Similar conditions might exist in the crank shaft illustrated in Figure 6.

A is the frame of a thrasher. B is a portion of the housing of a thrasher. C is a straw 80 rack and C' is a grain pan.

D is a crank shaft having a pair of crank pins D¹ D¹ and another pair of pins D² D². Upon each of the crank pins D¹ D¹ is mounted one end of a pitman D³, the other end of 85 which is pivoted to the straw rack at D⁴. Mounted at one end on each of the pins D² is a pitman D⁵, each of which pivoted at its opposite end at D⁶ on the grain pan C'. The crank shaft D is carried in bearings D⁷ supported from a frame A and has at one end a driving pulley D⁸.

In the diagram shown in Figure 4 the crank shaft X has a pin X¹ and a pin X². They are 95 placed as shown 180° apart, and the vibrating or reciprocating members of the machine which are driven from these cranks through the two pitmen, do not reach the end of their strokes simultaneously. This is a condition 100

which is essential for proper balancing when two such reciprocating members are employed.

A pitman is attached to each of the crank pins at one end and at the other end to a member which is reciprocated. In the apparatus to which the present application relates generally, the pitmen will be attached one to a grain pan and the other to a straw rack, the two being mounted to reciprocate along parallel lines. The length of travel of each of the reciprocated parts is indicated by the lines X^3 X^3 and X^4 X^4 .

The line X^5 indicates diagrammatically the pitman extending to the upper reciprocating member, and the line X^6 indicates similarly the pitman extending to the lower reciprocated member. As the crank rotates in the direction of the arrow, the pin X^2 moves clockwise, and it is moving away from the member to which its pitman is attached. Thus this member starts its movement to the left from the point shown in the drawing. The member to which the pitman X^6 is attached, which has moved to the right until it has reached the position shown in full lines in the figure, now reverses its direction and moves to the left. The member to which the pitman X^5 is attached has been moving to the left until the pin reaches the position shown in full lines. As rotation of the crank continues this member does not yet reverse its direction. It will not reverse its direction until the line of the pitmen has crossed the center line or axis of the crank, then it will reverse its direction and commence to move to the right. Thus it is obvious that when the crank pins are 180° apart the members to which the pitmen are attached do not reverse their direction of movement at the same time and there is an interval during which the reciprocated members are moving in the same direction and there is therefore an interval of unbalance. It is one of the objects of this invention to provide a crank arrangement whereby the movement of the reciprocated parts is reversed at the same time so that the two parts are never moving in the same direction and so that they are therefore always in a condition of balance; so that for a brief interval they are standing still, or changing their direction of movement, or else moving in opposite directions.

In Figure 5 is shown an arrangement of my invention whereby with a two throw crank shaft two members may be reciprocated in opposite directions and always in balance. While I shall describe this form of the invention as having a two throw crank shaft and two pitmen, it is obvious that this number might be multiplied and there might be a pair of throws and pairs of pitmen or any other such arrangement.

In the form shown in Figure 5 the crank 1 corresponds to the crank X^2 of Figure 4, and

the crank 2 corresponds to the crank X^1 of that figure. It will be noticed that the crank 2 has been shifted from its location directly opposite crank 1 so that the angle between the two crank pins 1 and 2 is equal to 180° minus the angle α . This angle α is the angle between the mean center line of the pitmen and cranks 1 and 2. The meaning of the expression "mean center line" will be clear from Figure 5 in which there is shown at the top of the figure a diagram indicating the length of travel of the member to which the pitman, which is attached to crank 2, is attached. Y represents the left limit of the travel, and Y^1 the right limit. It will be seen that Y^2 is the mean center line of the angle of travel of the pitman which is attached to the crank 2. The line Y^3 is the mean center line of the angle of travel of the pitman which is attached to the crank 1.

When rotation of the shaft, as shown in Figure 5, takes place in the direction of the arrow, the pin 1 moving clockwise starts its movement to the left and thus the member to which it is attached commences moving to the left. At the same time the pin 2, moving clockwise has already commenced its movement to the right, although the reciprocating member to which it is attached has just reached its extreme left position and is therefore ready to commence its movement to the right, thus the two reciprocating members reverse their direction at the same time. This will always take place so that they move in balanced relation.

Thus the member driven by the pitman attached to crank 2 reaches its inner or left dead center at the same time that the member driven by the pitman attached to the crank 1 reaches its outer or right dead center. This brings the movement of the reciprocating members driven from each of the two cranks into phase. The only error between their movements and the true sinusoidal movement is that due to the angularity of the respective pitmen, due to their having a finite length, and to the shifting of the reciprocating end of the pitmen, due to such parts being mounted on swinging hangers rather than upon surfaces within the plane of the crank shaft axis. It is this latter component of motion creating, as it does, a condition comparable to that in an engine having offset connecting rods, which introduces such kinematic complications as to cause us to consider the whole system on the basis of mean center lines of pitmen, rather than upon the inside or outside center lines.

In the form shown in Figure 6 the crank shaft is formed to provide for three reciprocating members which it is desired to balance by having their respective dead centers 120° apart, measured in respect to the crank shaft center. Pitman 4 is spaced from the mean center line of pitman 3 by the angle

a, and pitman 5 is likewise spaced from the mean center line of pitman 3 by the angle "b". The order of reciprocation is such that crank 3^a shall bring its corresponding reciprocating member to the inside or right dead center, followed by crank 4^a and then by crank 5^a. The normal spacing of a three throw crank, is that cranks 3^a, 4^a, and 5^a will be equally spaced 120° apart. Due to the angles "a" and "b" between the several pitman systems, it will be seen that the included angle between cranks 3^a and 4^a will be equal to the normal angle (120°) minus the angle "a" between the mean center line of pitman 3 and the mean center line of pitman 4, when measured as described above with reference to Figure 5. Likewise pitman 5 which would normally be spaced 240° from the mean center line of pitman 3 is spaced 240° minus the angle "b", the angular difference between the mean center line of pitman 3 and pitman 5.

Although I have shown an operative device, still it will be obvious that many changes might be made in size, shape and arrangement of parts without departing materially from the spirit of my invention; and I wish, therefore, that my showing be taken as in a sense diagrammatic.

The use and operation of my invention are as follows:

As shown in the first three figures a four throw crank shaft is used, the throws or crank pins being in pairs. Conditions are those described and shown in detail in connection with Figure 5.

There are two reciprocating parts, a straw rack and a grain pan. These two are reciprocated from the crank by means of the pitmen. The balanced condition described in detail in connection with Figure 5 exists in the form of the invention shown in Figures 1 to 3, and the straw rack and grain pan thus move in the opposite direction and they reverse their direction of movement at the same time.

I claim:

1. In a thrasher, a plurality of members mounted for reciprocation and means for reciprocating them in balanced relation, said means including a rotating crank shaft, said shaft so formed that the members all reverse their direction of movement at the same time, said members mounted one above the other, the axle of the crank shaft being positioned below the lowest member.

2. In a thrasher, a plurality of members mounted on different levels for reciprocation and means for reciprocating them in balanced relation, said means including a rotating crank shaft, said shaft so formed that the members all reverse their direction of movement at the same time, said members mounted one above the other, the axle of the crank shaft being positioned below the lowest member.

3. In a thrashing machine a plurality of members mounted on different levels for reciprocation, means for reciprocating them and for causing them to move in balanced relation, including a rotating crank shaft from which they are driven, said shaft provided with a plurality of crank pins or throws, the same being so arranged with relation to each other that they cause the members which are driven from them to reverse their direction of movement at the same time, said members mounted one above the other, the axle of the crank shaft being positioned below the lowest member.

4. In combination a plurality of parts separately mounted for reciprocation and means for moving them in balanced relation including a rotating crank shaft having a pin or throw for each such part and a pitman connecting each such part to its pin, each throw being spaced from its adjacent throw a distance equal to 360° divided by the total number of throws minus the angle included between the mean center line of the two adjoining pitmen, said members mounted one above the other, the axle of the crank shaft being positioned below the lowest member.

5. In combination a plurality of parts separately mounted for reciprocation on different levels and means for moving them in balanced relation including a rotating crank shaft having a pin or throw for each such part and a pitman connecting each such part to its pin, each throw being spaced from its adjacent throw a distance equal to 360° divided by the total number of throws minus the angle included between the mean center line of the two adjoining pitmen, said members mounted one above the other, the axle of the crank shaft being positioned below the lowest member.

6. In combination a pair of parts separately mounted for reciprocation and means for moving them in balanced relation including a rotating crank shaft having a pair of pins or throws and a pitman connecting each part with one of such pins, the pins being spaced apart a distance equal to 180° minus the angle included between the mean center line of the two pitmen, said members mounted one above the other, the axle of the crank shaft being positioned below the lowest member.

7. In combination a pair of parts separately mounted for reciprocation on different levels, and means for moving them in balanced relation including a rotating crank shaft having a pair of pins or throws and a pitman connecting each part with one of such pins, the pins being spaced apart a distance equal to 180° minus the angle included between the mean center line of the two pitmen, said members mounted one above the other, the axle of the crank shaft being positioned below the lowest member.

other, the axle of the crank shaft being positioned below the lowest member.

8. In a thrasher, a plurality of members mounted for reciprocation and means for reciprocating them in balanced relation, said means including a rotating crank shaft mounted beneath such members, said shaft so formed that the members all reverse their direction of movement at the same time, said members mounted one above the other, the axle of the crank shaft being positioned below the lowest member.

9. In a thrasher, a plurality of members mounted on different levels for reciprocation, and means for reciprocating them in balanced relation, said means including a rotating crank shaft mounted below such members, said shaft so formed that the members all reverse their direction of movement at the same time, said members mounted one above the other, the axle of the crank shaft being positioned below the lowest member.

10. In combination, a plurality of members separately mounted for reciprocating movement on different levels and means for moving all of them in balanced relation including a rotary crank shaft having a pin or throw for each such part, and a connecting rod connecting each such part to its throw, each crank throw being formed in a plane inclined to the plane of the adjacent crank throw at an angle equal to the average inclination of the plane of the connecting rod attached to said crank throw throughout the several positions of movement of said connecting rod, said members mounted one above the other, the axle of the crank shaft being positioned below the lowest member.

Signed at Battle Creek, county of Calhoun, and State of Michigan, this 18th day of January, 1926.

WAYNE H. WORTHINGTON.
